M. WEIWODA.

FLOAT VALVE FOR CARBURETERS.
APPLICATION FILED FEB. 15, 1910.

1,022,392.

Patented Apr. 2, 1912.

UNITED STATES PATENT OFFICE.

MATHIAS WEIWODA, OF NEW YORK, N. Y., ASSIGNOR TO GEORGE W. STEVENS, OF NEW YORK, N. Y.

FLOAT-VALVE FOR CARBURETERS.

1,022,392.

Specification of Letters Patent.

Patented Apr. 2, 1912.

Original application filed February 20, 1909, Serial No. 479,045. Divided and this application filed February 15, 1910. Serial No. 543,959.

To all whom it may concern:

Be it known that I, MATHIAS WEIWODA, a citizen of the United States, and a resident of the city of New York, borough of Brooklyn, in the county of Kings and State of New York, have invented a new and Improved Float-Valve for Carbureters, of which the following is a full, clear, and exact description.

10 This invention relates to certain improvements in carbureters, and more particularly to the means for supplying the liquid fuel to the vaporizing chamber and maintaining said fuel at the desired level.

15 My improved liquid-controlling means is preferably used in connection with the carbureter claimed in my previous application, Serial No. 479,045, filed February 20, 1909, of which application this is a division, but 20 it is evident that said liquid-controlling means could be used in various other forms of carbureters and for controlling the liquid in other chambers.

The special object of my invention is to 25 so construct and mount the float and float valve, that it may be readily removed from the liquid chamber without disassembling the latter or without removing any of the other parts of the carbureter. The float 30 and all of the parts connected therewith are mounted on a single closure plate covering an aperture in one wall of the chamber, so that by removing this plate, the float and all of the liquid level controlling means are 35 moved.

Reference is to be had to the accompanying drawing, forming a part of this specification, in which the figure is a central vertical section through a carbureter constructed 40 as disclosed in my prior application above referred to, and having a liquid-controlling means constructed in accordance with my present invention.

In the carbureter illustrated there is provided an outer sheet metal casing 10, having a chambered cover 11, a plurality of vertically-disposed fabric plates 12, and a plurality of air supply pipes 13. The air enters through a conduit 14 to an annular 45 chamber 15 in the cover, thence downwardly through the pipes 13 into the liquid, and then up along the surfaces of the moist fabric plates 12, and out through a series of telescoping baffle sections 16. Above the

baffle sections is a central chamber 17, and 55 mounted on the top of the carbureter and receiving the explosive charge from said chamber, is a valve casing and throttle valve 18. All of these parts are constructed substantially as shown in my previous application 60 above referred to, and further detail description need not be given herein.

The bottom baffle section, 19, is closed across its lower end and directly below this section is mounted my improved liquid-controlling means, which serves to deliver liquid fuel to the casing 10 and maintain it at the desired level in respect to the plates 12 and pipes 13. The bottom of the casing is provided with a threaded opening 65 normally closed by a plate 22, which plate has a central aperture 23 therethrough. Surrounding the aperture is a boss 24, to which is connected a liquid delivery pipe 25, by any suitable form of coupling, as, for 70 instance, a collar 26. Within the boss 24 and held in place by the pipe 25, I employ a screen for preventing impurities and solid particles from passing into the casing with the liquid. In order to give the screen the 75 maximum surface and to prevent it from becoming clogged by the accumulation of impurities, the screen is preferably formed of a multiplicity of connecting conical portions. As shown, there is employed an 80 outer truncated conical portion 27, having its periphery secured in place intermediate the ends of the boss 24 and the end of the pipe 25, and at the smaller end of this truncated conical portion is an inner and inverted conical portion 28. The two conical portions together present a large surface 85 through which the liquid may pass and reduce to a minimum the liability of any 90 clogging by the accumulation of solid particles.

At the inner end of the aperture 23 is a valve seat for receiving a vertically-movable valve 29, and encircling the valve stem 30 of said valve is a float 31. Below the float 100 are levers 32, fulcrumed on bosses extending upwardly from the plate 22 and having their outer ends pivotally connected to the float and their inner ends connected to the valve, whereby as the liquid accumulates 105 within the lower portion of the casing, the float may rise to force the valve downwardly against its seat and prevent the further ad-

mission of liquid. The float is somewhat smaller than the plate 22 and is preferably inclosed within a small casing 33 carried by the plate 22. This casing also serves as a 5 guide for the upper end of the valve stem 30. As all of these parts are smaller than the opening in the bottom of the casing, and as they are all carried by the plate 22, it is evident that by unscrewing this plate and 10 removing it from the main casing, the valve, float, casing 33, levers 32 and screws can be removed without disassembling the remainder of the carbureter.

The casing 33 is spaced from the bottom 15 baffle section 19 by a spring 39, which tends to hold all of the casing sections in their proper relative positions, and prevents any rattling of the parts. The fabric plates 12 are all supported at their lower ends on a 20 plate 20, having a central aperture through which the casing 33 extends, so that said casing 33 tends to prevent the fabric plates and the supporting plate 20 from moving laterally or becoming displaced. The closure 25 plate 22 also carries a pet cock 40, by means of which the carbureter casing 10 may be drained.

The carbureter casing is preferably formed 30 from thin spun metal, while the closure plate 22 is formed of a casting. It will be noted that all of the operating parts connected with the filling or emptying of the carbureter casing with liquid, are connected to this cast metal closure plate rather than to 35 the wall of the carbureter itself.

Various changes may be made in the construction and operation of the parts within

the scope of the appended claims, and without departing from the spirit of my invention.

40

Having thus described my invention, I claim as new and desire to secure by Letters Patent:

1. In a float feed mechanism, a casing having an opening in the lower end thereof, 45 a plate constituting a closure for said opening and having an aperture therethrough, a liquid-delivery pipe detachably secured to said plate at the outer end of said opening, a valve within said casing for closing said 50 aperture, a float adjacent said valve, levers pivoted to said plate and having operative engagement with said float and said valve, and a cage inclosing said float, levers and valve and secured to said plate, said cage, 55 float and valve being removable through the opening in said casing, upon the removal of said plate.

2. A float feed for a tank, comprising a casing provided with an opening in the wall 60 thereof, a plate adapted to close said opening, a delivery pipe connected to said plate and delivering through the same, a float valve casing carried by said plate upon the inner side thereof, and a float valve within 65 said casing controlling the passage of fluid from said delivery pipe.

In testimony whereof I have signed my name to this specification in the presence of two subscribing witnesses.

MATHIAS WEIWODA.

Witnesses:

C. R. GRIFFIN,
LEO J. CURREN.
